UNITED STATES PATENT OFFICE.

ROBERT S. WHEELER, OF GRENLLOCH, NEW JERSEY.

COTTON-GIN.

1,340,691.

Specification of Letters Patent.

Patented May 18, 1920.

Application filed April 11, 1919. Serial No. 289,250.

To all whom it may concern:

Be it known that I, ROBERT S. WHEELER, a citizen of the United States, and resident of Grenloch, New Jersey, have invented certain new and useful Improvements in Cotton-Gins, of which the following is a specification.

My present invention relates to improvements in cotton gins and has among its objects the following:

First to provide a gin that will not cut, break, or otherwise injure the fiber of the cotton in any way, but on the contrary will improve the staple by giving a fiber the full length it grew.

Second to secure a gin that will remove all trash and dirt.

Third to provide apparatus that is portable, and may be used in connection with a cotton picker, such for example as shown in my United States Patents Numbers 922,647 and 1,001,720; to gin the cotton as fast as it is picked, delivering the seed into one receptacle and the lint into another, or into a press on the same truck that carries the motive power, thus doing the extra work of ginning without the expense of any extra labor, or time and very little more power.

Fourth to provide a gin that will clean the seed under all conditions, cleaner than it is now done.

Finally to provide a gin of low cost, simple and requiring little power to operate.

With these and other objects in view the invention includes the novel features of construction and arrangement and combination of parts hereinafter described and particularly defined in the appended claims.

An embodiment of my invention is illustrated in the accompanying drawings, in which,

Figure 1 is a side elevation.

Fig. 2 is an end view.

Fig. 3 is a plan view.

45 Figs. 4, 5 and 6 are views of details.

Fig. 7 is a detail view of card clothing.

Referring by reference characters to this drawing A designates a pipe by which the cotton is conveyed from a suitable source to a hopper B, where it comes in contact with an endless traveling surface of card cloth which may conveniently be in the form of an endless belt C passing around the drums C' and C².

55 As the cotton is carried by the belt from

the hopper it passes beneath a plurality of presser feet D which insures its being brought into firm contact with and attached to the belt. From these presser feet the cotton is carried by a plurality of breasts or 60 rows of seed arresters E. These are diagonally arranged feet or short bar members which may be conveniently suspended by vertical rods or bars F from the top frame member W.

65 The first seed arresters are set higher above the belt than those following and are so located as to allow the seed, while thickly covered by cotton, to be pulled under them.

The following arresters are set closer to 70 the surface of the belt so that the seed must pass around them, and they are also placed at a greater angle to the line of travel of the belt, so that as the seeds are cleaned and the card cloth or belt loses its hold on them the 75 arresters will push them faster toward the edge of the belt.

The arresters therefore have a carding action as each arrester only slightly checks the seed that strikes it, giving it at the same 80 time a little roll or push away from its line of travel while the lint that is fast on or adhering to the belt continues on in a straight line. Each time, therefore, that a seed is checked, no matter how slightly, a 85 part of its lint is gently pulled off right at the seed which is the weakest place and the lint is not broken or cut but preserved in its full length.

One or more sets of wire arresters G or 90 brushes are provided at suitable points on the gin-belt to prevent cotton, fine trash or small seeds from bedding down into the card cloth and thus missing the seed arresters, and also to prevent clogging of the 95 gin belt, as they will hold back the cotton and allow only just what the card cloth will grasp to go through, and in this way every seed will be acted upon by the arresters.

At the inner end of the belt is provided 100 an apron H, or final trash and small seed arrester, which is set at a suitable angle across the gin belt. The trash and seed from which the lint has been removed, will be pushed upon this and the air blast from 105 air pipes P (Figs. 1, 2 and 3) will blow them into seed trough L, from which they may be removed by conveyer pipe M, containing conveyer screw N, and deposited into a sack or other receptacle (not shown). 110

The lint is removed from the card clothing belt, or gin belt, by a doffer brush I of any suitable construction from which it is thrown by centrifugal force into box J, and 5 removed through conveyer pipe by an air blast to a press or other receptacle on the truck (not shown).

Beneath the gin belt is a table S or bridge to prevent it from sagging or in any way 10 getting away from the arresters so that they will not act properly. This table is representative of any suitable supporting means.

A tightener pulley Q may be used on gin belt, if desired, with springs R, R, to give 15 it the proper power.

The bearings that carry the pulley C' are mounted in movable bearings and provided with adjusting screws and springs T, T, (Figs. 1 and 3) to keep the gin belt at proper 20 tension. These bearings, also the ones for the pulley C² are made easily removable, so that the gin belt may be removed without trouble.

A power shaft U and gearing V (Figs. 1, 25 2 and 3) are shown as examples of suitable means for driving the drum C' and brush and the seed conveyer screw N may be driven by a flexible shaft O, from end of shaft that carries pulley C².

30 What I claim is:

1. In combination an endless moving ginning element, means for feeding cotton to be ginned thereto, and a plurality of successively located stationary arresters arranged 35 in proximity to the surface of said element, said arresters being oblique to the line of travel, each successive set of arresters being of increased obliquity.

2. In combination an endless moving ginning element, means for feeding cotton to be ginned thereto, and a plurality of successively located diagonally arranged arresters located in proximity to the surface of said 40 element.

45 3. In combination an endless moving ginning element, means for feeding cotton to be ginned thereto, and a plurality of successively located stationary arresters arranged in proximity to the surface of said element, the succeeding arresters being nearer to the 50 surface of the element than the preceding ones.

55 4. In combination an endless moving ginning element, a hopper for holding cotton in contact therewith, presser means for

pressing the cotton onto the surface of said element, and a plurality of diagonally arranged arresters in proximity to the surface of said element.

5. In combination an endless moving ginning element, a hopper for holding cotton in contact therewith, presser means for pressing the cotton onto the surface of said element, and a plurality of diagonally arranged arresters in proximity to the surface of said 65 element, and a seed and trash collector at the side of said element.

6. In combination an endless moving ginning element, a hopper for holding cotton in contact therewith, presser means for pressing the cotton onto the surface of said element, and a plurality of diagonally arranged arresters in proximity to the surface of said 70 element, and a collecting apron acting on said element after it has passed the arresters. 75

7. In combination an endless moving ginning element, a hopper for holding cotton in contact therewith, presser means for pressing the cotton onto the surface of said element, and a plurality of diagonally arranged 80 arresters in proximity to the surface of said element, and a collecting apron acting on said element after it has passed the arresters, and a doffer brush acting on said element after it leaves the apron. 85

8. In combination an endless traveling belt, means for supplying cotton thereto and a plurality of rows of diagonally placed arresters arranged at different elevations above the belt and at varying degrees of inclination 90 to the line of travel.

9. In combination an endless moving ginning element, means for feeding cotton to be ginned thereto, a plurality of successively located stationary arresters arranged in 95 proximity to the upper surface of said element, and means located on the under surface of said element for maintaining it in proper relation to the arresters.

10. In combination an endless moving 100 ginning element, means for feeding cotton to be ginned thereto, a plurality of successively located stationary arresters arranged in proximity to the upper surface of said element and means for maintaining the 105 surface of said element in proper relation to the arresters.

In testimony whereof I affix my signature.

ROBERT S. WHEELER.
